United States Patent Office

Des. 194,870
Patented Mar. 26, 1963

194,870

ELECTRICAL OUTLET

Carl A. Hill, 323 N. Pine St., St. Louis, Mich.

Filed July 25, 1960, Ser. No. 61,499

Term of patent 14 years

(Cl. D26—1)

FIG. 1 is a bottom front perspective view of an electrical outlet, showing my new design; and

FIG. 2 is a top rear perspective view thereof.

I claim:

The ornamental design for an electrical outlet, substantially as shown.
